(57) **CLAIM**

The ornamental design for a spacesaver cabinet, as shown and described.

DESCRIPTION

FIG. 1 is a perspective view of a spacesaver cabinet showing our new design;

FIG. 2 is a perspective interior view thereof with the cabinet doors removed for completeness of illustration;

FIG. 3 is a front elevational view thereof;

FIG. 4 is a top plan view thereof; and,

FIG. 5 is a left side view thereof; the opposite side being a mirror image of the side shown.

The broken lines are for illustrative purposes only and form no part of the claimed design.
